UNITED STATES PATENT OFFICE.

HOWARD H. DUDLEY, OF KANSAS CITY, MISSOURI.

STOCK-CAR.

1,081,588.

Specification of Letters Patent. Patented Dec. 16, 1913.

Application filed January 28, 1911. Serial No. 605,308.

To all whom it may concern:

Be it known that I, HOWARD H. DUDLEY, a citizen of the United States, residing at Kansas City, in the county of Jackson and 5 State of Missouri, have invented certain new and useful Improvements in Stock-Cars, of which the following is a specification.

My invention relates to stock cars and has for its object to provide a car which may 10 easily and quickly be converted from a single to a double deck structure or vice versa, to adapt it for use in hauling cattle or horses, or when converted for hauling sheep, hogs, etc. In accomplishing this object I have provided the improved details of 15 structure which will hereinafter be fully described and are illustrated in the accompanying drawings, wherein:—

Figure I is a side view of the body of 20 a stock car constructed according to my invention, a part of the upper portion of the car being broken away to more clearly illustrate the interior construction. Fig. II is an end view of the car. Fig. III is a vertical section on the line III—III, Fig. I. Fig. IV is a horizontal section on the line 25 IV—IV, Fig. I. Fig. V is an end view of a part of the car, showing the bracket locking lever in open position. Fig. VI is a detail 30 perspective of the lever and its locking bracket. Fig. VII is a vertical section on the line VII—VII, Fig. IV. Fig. VIII is a horizontal section on the line VIII—VIII, Fig. I, illustrating the deck latches. Fig. 35 IX is a vertical section on the line IX—IX, Fig. IV, showing a deck tightening screw.

Referring more in detail to the parts:— 1 designates an ordinary railway box car having the flooring 2, side posts 3, end 40 posts 4 and roof beams 5, such parts being of a well known and ordinary construction.

Located within the car and spaced from the sides and ends thereof, to have free vertical movement therein, is an auxiliary flooring 45 6, which may be of any convenient construction, but of sufficient strength to support a substantial weight.

Journaled in bearings 7 in the roof beams 5 are the windlass shafts 8, the ends of 50 which project through the ends of the car and have hand wheels 9 rigidly secured thereto. Also fixed on the shafts 8 are ratchet wheels 10, and pivotally mounted on a convenient part of the main car structure are pawls 11 which are adapted for co-

operation with the ratchets 10 in the usual manner.

Anchored on the windless shafts 8 are ropes 12, which depend in the car and are fixed to the auxiliary deck 6, so that by turning the hand wheels 9 the auxiliary deck 60 may be raised or lowered.

Attached to the faces of the side posts 3 are plates 13, and pivotally mounted in said plates are bars 14, to which are firmly 65 attached the deck supporting brackets 15, each bracket having an inside section adapted to rest on one of the longitudinal beams 16 of the car structure and an outside section 17 for engaging the under edge of a 70 keeper beam 18 that is fixed to and extends longitudinally between the side posts 3.

Pivotedly mounted on the roof beams 5 at the outside of each end of the car are the levers 19 having rods 20 extending into 75 proximity to the ends of the bracket bars 14 and having handle portions 21 projecting inwardly into proximity to the hand wheels 9.

Rigidly fixed to the end of each bracket 80 beam 14 is a crank 22, which in turn is pivotally connected with the lower end of a lever rod 20. Also fixed to the roof beams 5 are latch keepers 23, which are preferably formed of channel metal, the flanges of 85 which open outwardly and are provided with apertures 24 through which the pins 25, that are chained to the car roof, may be carried.

In side beams 26 on the car body and in 90 end posts 4, about half way up on the car, and also preferably in the same parts, near the bottom of the car, are threaded sleeves 27. Threaded into each sleeve 27 is a rod 28, the inner end of which is adapted to bear 95 against the side or end of the auxiliary deck when the latter is in position at the center or bottom of the car, and the outer end of which is provided with a hand-wheel 29. In order to save wear on the deck, at the point 100 of engagement of the rod 28, I prefer to provide the deck with metal plates 30, against which the ends of the rods may bear.

In order to lock the deck in place, I provide the side posts, adjacent to the door 105 openings, with horizontally arranged sockets 31 and the deck with collars 32 and with stop lugs 33 which are arranged in line with the collars 32, but spaced therefrom sufficiently to admit the shank 34 of a locking 110

pin 35 therebetween. With this construction, when the floating deck is in place, the pin 35 may be inserted into the socket and the shank turned downwardly into the space 5 between the collar and lug. To unlock the deck it is only necessary to remove the pin from the socket. It is apparent that when the pin is in place it cannot be accidentally withdrawn because of the position of the lug 10 33 which limits the travel of the pin shank. Presuming a car to be equipped with an auxiliary deck and operating parts as described, the use of the car is as follows: For hauling cattle or large stock, the 15 auxiliary deck is either lifted to the top of the car and held in elevated position by the ratchets on the windlass shafts, or is lowered to the bottom of the car and held in place by tightening the rods 28 against the sides 20 and ends thereof, the auxiliary deck supporting brackets 15 being held in elevated position by turning the lever handles 20 outwardly and locking same in the keepers 23, as illustrated in Fig. V, in which position the supporting brackets will be held 25 vertically as shown in Fig. VII. When it is desired to convert the car to a double deck structure for hauling sheep or other small stock, the auxiliary deck, if located at the 30 bottom of the car, is released by the rods 28 and lifted about the center of the car, by operating the hand wheels 9 to withdraw the rope on the windlass shafts. The lever arms 21 are then turned back toward the 35 center of the car, the rods 20 lowering the brackets 15 until their inside sections rest

on the beam 16 and their outside sections engage the under faces of the keeper beams 18. The deck is then lowered onto the brackets, by which it is supported, and 40 tightened in place by screwing the rods 28 against the sides and ends. The deck when in this condition will be as substantial as any permanent upper deck, and the car may be used in the usual manner. The manner 45 of converting the car back to its original condition is apparent from the description of the operation of arranging the parts for the double deck structure.

Having thus described my invention, what 50 I claim as new therein and desire to secure by Letters-Patent is:—

1. In a stock car, a car body having vertical sides, a vertically movable deck between said sides, and horizontally adjustable 55 means supported by said sides for engaging with and holding said deck against horizontal movement.
2. In a stock car, a car body having vertical sides, a vertically movable deck between 60 said sides, and horizontal screws having threaded connection with said sides and adapted to bear against and hold said deck against horizontal movement.

In testimony whereof I have signed my 65 name to this specification in presence of two subscribing witnesses.

HOWARD H. DUDLEY.
